GARMENT

Filed April 3, 1928

UNITED STATES PATENT OFFICE.

SELMA E. SZAKVARY, OF NEW YORK, N. Y.

GARMENT.

Application filed April 3, 1928. Serial No. 266,933.

This invention relates to a garment of the snug-fitting corset type which by reason of its close-fitting conformation closely extends about and shapes the trunk portion of the body accordingly.

Garments of this general character are at the present time so made that their upper end begins either at or above the waist line and their lower end extends downwardly for 10 a considerable distance and terminates below the hips and in some cases extends for some distance on the thighs. Garments of this character, and particularly those of the tubular elastic "slip-on" type which have no 15 lacing or openings of any kind, have been found inconvenient in some particulars and especially so when adjustment or shifting of the lower portions of the garment is necessitated for the purpose of rendering parts of 20 the body accessible for sanitary purposes.

The object of this invention therefore is to provide a corset-like snug-fitting garment which may or may not as desired, be provided with lacings or other adjustments, and which 25 will by reason of my improved construction be provided with means for permitting immediate accessibility to parts of the body required to be rendered accessible for sanitary purposes. I attain this end without in any 30 way altering the general shape of the garment and without the utilization of any bulky or inconvenient fastening devices or supplemental panels or flaps, which means have undoubtedly been used in the past and which 35 have defeated the purpose of a corset by producing doubled or thickened parts on the garment thereby destroying the smooth outer conformation and appearance of the corset and such other outer garments as may be 40 worn over it.

Through the use of my improved construction, the garment may be of such length as is required to properly shape the wearer's body without in any way discommuning the 45 wearer; it may also be more readily placed on and removed, and is so designed that it cannot by any possibility cause inconvenience or discomfort while being worn, but will on the other hand afford the uses and desirability of the long close-fitting elastic garment so preferred at the present time without in 50 any way inconveniencing the wearer of such garment.

Reference is to be had to the accompanying 55 drawing, forming a part hereof in which

Figure 1 is a rear view of a garment made in accordance with my invention; and

Figure 2 is a view of the lower part of the garment at the rear thereof showing the 60 raisable flap in its lifted position.

Throughout the various views of the drawings, similar reference characters designate similar parts.

In the embodiment of my invention shown in the accompanying drawing, 1 indicates the 65 front of the body of the garment disclosed and 2 indicates the rear thereof. The garment shown is a snug fitting undergarment of the corset type which is adapted to fit about and embrace the hips and surrounding 70 parts of the body.

The upper edge of the garment shown is indicated at 3 and the lower edge at 4. The garment is of such length that the upper edge 3 usually terminates at or slightly above the 75 waist line, the lower edge 4 extending a considerable distance below the hips and in some garments well down on the thighs.

At 5 and 6 are shown elastic inserts which permit the garment to be sufficiently expanded, since it is of tubular closed form, to be fitted on the wearer and also provide the necessary elasticity to cause the garment to very snugly embrace and compact the wearer's 80 form. The front portion of the garment 85 shown at 1 is preferably an insert of inelastic material or fabric and it is provided with a plurality of elongated pockets 7 which are used to enclose suitable stays 8 in the conventional way.

At the back of the garment, I provide a pair of slits 9 which slits begin at the lower edge of the garment and extend upwardly for a relatively short distance, where they terminate. These slits terminate at a considerable 95 distance below the upper edge 2 of the garment and they are preferably located at the longitudinal side edges of the inelastic reinforcing piece 2 found on the back of the garment. The section of the garment located 100 between these slits, which section consists of the lower extremity of the part 2, is formed by reason of the slits, into a raisable flap portion 10 when the slits are opened. Thus, through the medium of the slits 9, I provide 105 such raisable flap portion which can be conveniently and readily lifted to render accessible those parts of the body required for sanitary purposes.

To close these slits when desired, I pro- 110

vide releasable fastening means 11, such fastening means being located in the slits and being in the form of hooks located on one side of the slit that engage with complementary members on the opposite edge of the slit. By movement of a slide member 12, the fastening members may be engaged to close the slit or disengaged to open the slit by a reverse movement of the slide. It will be noted that the slits are in their open condition when the slides 12 are at the upper end or termination of the slit.

In order to permit free lifting movement of the flap 10 without interference by the stays 8, it may be desirable to terminate these stays at a point located at or near the upper upper end of the slits 12 as is clearly shown in Figure 1.

To protect the wearer's body from contacting with the fastener members 11, I find it desirable to provide the inner face of the garment with a flap member 13 that underlies the slits 9 and consequently the fastener members located in said slits. The lower end of each of these flaps 13 is provided with a snap fastener member 14 that engages with a complementary fastener member 15 located on the inner face of the body of the garment.

From the foregoing, the construction and use of my improved garment will be readily understood. It will be seen that the garment in normal wear is completely closed and provides a very smooth and snug fitting construction. When for sanitary purposes it is required to raise the flap 10, this can be very quickly and effectively done by moving the two slide members 12 up to the top of their respective slits 9 to cause the fastening means to open. The flap may then be raised as required.

To close the slits 9 and cause the flap portion 10 to again form an integral part of the garment, the slides 12 are moved downwardly to their limit.

While I have shown my improved construc-

tion applied to a certain type of completely closed tubular corset-like garment, it will be obvious that this construction may well be applied to any type of snug fitting garment of the same general character and is most applicable to that type of garment which extends well down below the hips and which has been found inconvenient for many reasons readily understood.

The type of fastening means which I employ for closing and opening the slits may be varied in many ways, provided such type of means be employed as will permit a ready opening and closing action of the slits when desired.

Having described one embodiment of my invention, it is obvious that the same is not to be restricted thereto, but is broad enough to cover all structures coming within the scope of the annexed claim.

What I claim is:

A close-fitting corset-like garment of closed, continuous tubular expansible form having elastic and inelastic panels, said garment being provided at the back with a pair of spaced slits located at the opposite side edges of one of the inelastic panels and extending upward for a short distance from the lower edge of the body of the garment, that integral continuous portion located between the slits forming an inelastic raisable flap when the slits are open, fastening means for drawing together the edges of the elastic panels and the edges of the inelastic flap and closing the slits therebetween, said means comprising a plurality of fastener elements located on opposing edges of the slits and adapted to be interengaged by movement of slides, and protective flaps located within the garment and covering the slits and fastening means, and means for detachably securing said flaps to the garment body.

Signed at the city, county and State of New York, this 31 day of March, 1928.

SELMA E. SZAKVARY.
